(57) CLAIM

The ornamental design for a stirrup, as shown and described.

DESCRIPTION

1.1 is a perspective view of an embodiment of a stirrup, showing our new design;

1.2 is a front view thereof;

1.3 is a rear view thereof;

1.4 is a left side view thereof;

1.5 is a right side view thereof;

1.6 is a top view thereof; and

1.7 is a bottom view thereof.

The broken lines shown in the drawings illustrate portions of the stirrup that form no part of the claimed design.
